ABSTRACT

For being used with a machine that applies glue to a container, a container portion and the like, an overhead glue pot assembly that includes side frame members dependently mounting a glue pan, and mounting a pick up roll to pick up glue from the pan, a premeter bar to strip off excess glue off the pick up roll, and a metering roll, a string trough for catching glue falling from the nip area of the transfer and pick up rolls, and a bracket having a spout receiving slot whereby the glue container that has an elongated slot can be tilted from a near horizontal condition with the spout in the glue in the pan to a seated position on the bracket that the spout extends vertically. The string trough extends further forwardly of the glue pan than the front wall.

OVERHEAD GLUE POT APPARATUS

BACKGROUND OF THE INVENTION

Overhead glue pot apparatus that includes a pick up roll and a glue pan.

In the prior art it is old to provide a stringer or return roll which have bearings and seals located below the level of the glue in the glue pan. Additionally with such stringer or return roll there is usually provided fixed scrapers or doctor blades. In order to obviate the need of such stringer or return roll and the usual accompanying fixed scraper or doctor blades, this invention has been made. Also this invention has been made to facilitate cleaning the glue pan without disassembly from the remainder of the glue pot apparatus. Further, this invention has been made to facilitate positioning a glue container in a seated position to dispense glue in the glue container without the dripping of glue outside of the glue pan. Additionally this invention has been made to solve other problems.

SUMMARY OF THE INVENTION

Overhead glue pot apparatus that includes a pick up roll to pick up glue from a glue pan, a metering roll for controlling the amount of glue on the pick up roll that is available for transfer to a transfer roll of the machine with which the glue pot apparatus is used, and a removable string trough for catching glue falling from the nip portions of pick up roll and transfer roll that does not fall into the pan.

One of the objects of this invention is to provide in overhead glue pot apparatus, a glue pan of a new and novel configuration to facilitate cleaning the pan without disassembling said apparatus. Another object of this invention is to provide a new and novel string trough that is removably mounted adjacent the front wall of the glue pan for catching glue falling forwardly of the pan from the nip portions of the glue pick up roll of overhanging glue pot apparatus and the transfer roll of the machine with which said apparatus is used. An additional object of this invention is to provide new and novel structure stationarily mounted for stripping off excess glue that is picked up by the pick up roll of glue pot apparatus. A still further object this invention is to provide a new and novel bracket for mounting a glue container to dispense glue into a glue pan and a cooperating member on the container for releasably retaining the container on the bracket whereby the container can be moved from a generally horizontal position to a vertical condition while maintaining the discharge end of the spout of the container in overhanging relationship to the glue pan.

BRIEF DESCRIPTION OF THE DRAWINGS

FIG. 1 is a side view of the apparatus of this invention, other than that parts are broken away, the glue supply mechanism is shown in cross section, and the portion of the conveyor illustrated is shown much more closely adjacent the glue pan than it actually is;

FIG. 2 is a horizontal view, part in cross section, generally taken along the line and in the direction of the arrows 2—2 of FIG. 1;

FIG. 3 is a rear view, generally taken along the line and in the direction of the arrows 3—3 of FIG. 1, other than the glue container is not shown; and

FIG. 4 is an enlarged, fragmentary vertical cross-sectional view generally taken along the line and in the direction of arrows 4—4 of FIG. 2 to more clearly illustrate the string trough and the front part of the glue pot pan relative the glue pick up roll and the glue transfer roll.

Referring now to the drawings, the overhanging glue pot apparatus of this invention includes a frame having a pair of side frame members 12 and 13 which dependently mount the glue pan, generally designated 14, and extend along either side thereof. The glue pan includes a pair of side walls 15, a rear wall 16, a bottom wall 17 and a front wall 18.

Rotatably mounted by the side frame members to extend downwardly into the pan to pick up the glue therefrom is a glue pick up roll 20 which is of conventional construction. A sprocket 21 is keyed to the glue roll shaft 22 for drivingly rotating said shaft and thereby the glue roll 20 which is mounted on said shaft. A suitable drive connection 24 is provided between gear 21 and the motor 25. Conventional scrapers 23 are provided between the roll 20 and the side frame members.

Cutouts 26 are provided in the side frame members for mounting slide blocks 27 for limited horizontal movement, springs 28 on bolts 29 that are threaded into the side frame members resiliently urging the slide blocks in a forward direction toward the pick up roll. The slide blocks rotatably mount a shaft 30 which in turn mounts a metering roll 31 to rotate therewith. Through the aforementioned mounting of the metering roll, the springs 28 resiliently retain the metering roll in a selected spaced relationship to the pick up roll while at the same time permitting the metering roll moving away therefrom to permit lumps of hardened glue and foreign matter to pass between said rolls.

A gear 35 is keyed to the shaft 30 to be driveably rotated by gear mechanism 36, said gear mechanism in turn being driven by a gear 37 that is keyed to the shaft 22. The gear ratios are such that the metering roll rotates at a slower speed than the pick up roll.

Mounted by the side frame members at a lower elevation than the axis of rotation of the metering roll and slightly spaced from the exterior circumferential surface of the pick up roll is the premeter bar 40. The purpose of providing the premeter bar is to strip off part of the excess of glue that is picked up by the pick up roll and thereby decrease the amount of glue that is elevated adjacent to the metering roll which is vertically above the premeter bar and angularly spaced relative the metering bar in the direction opposite the direction of rotation 71 of the pick up roll.

A handle 42 is mounted by mounting members 43 which in turn are mounted by the side frame members. Extending between and bolted to side frame members is a mounting bracket 44 having notched portions 45 for attaching the apparatus of this invention to the machine with which it is to be used.

A bracket 48 is mounted on the bracket 44, bracket 48 having a horizontal leg 48a extending in overhanging relationship to the rear portion glue pan. Bracket 48 has an elongated slot 49 that opens at one corner portion thereof and extends diagonally such as shown in FIG. 2, there being provided a dowel aperture 50 through the horizontal leg that is spaced from slot 49.

The glue container, generally designated 54, has a container member 53, a cover 55 threaded thereon, the

cover having a central aperture through which the elongated spout 56 extends. The spout has an annular flange 56a within the cover that is secured to the cover by a screw 57 and a screw 58. The screw 58 has a dowel portion that extends outwardly beyond the cover for being extended into the dowel aperture when the container is mounted in a position of use with the flat circular surface seated on the bracket 48. To be noted is that the spout is of a sufficient length to extend downwardly into the glue pan when the container is mounted on a bracket 48.

In moving the container into a mounted position on the bracket, the spout is merely layed along the edge of the glue pan to extend generally horizontally with the discharge end of the spout overhanging the interior of the pan and then the glue container is tilted upwardly with the discharge end of the spout extending right into the glue in the glue pan almost immediately. The spout slips through the slot 49 and the container is moved such that the screw dowel end moves into the dowel aperture 50 to prevent the glue container from accidentally falling off the bracket 48, while permitting the container being moved vertically to remove the container from the bracket.

Referring in particular to FIGS. 1 and 4, the glue pot pan bottom wall 17 has a generally flat horizontal portion 17a that extends from a location beneath the pick up roll to the end wall 16 and an arcuately curved portion 17b having a radius of curvature emanating from the axis of rotation of the pick up roll, portion 17b underlying the lower most portion of the pick up roll and having one edge integrally joined to the adjacent edge of portion 17a and an opposite edge integrally joined to the front wall 18. Portion 17b extends to a substantially lower elevation directly beneath the lowermost part of the pick up roll than any other part of the bottom wall. The front wall is inclined upwardly and forwardly from portion 17b and has an upper edge almost directly beneath the nip formed by the pick up roll 20 and the transfer roll 65 of the machine with which the apparatus of this invention is used. For example wall 18 may advantageously be inclined at about 60° for a pick up roll of about a diameter of about 4 1/2 inches.

A string trough 66 has an upper portion 66a that underlies the wall 18, portion 66a having an upper edge almost directly beneath the aforementioned nip of rolls 20, 65. Further, the trough 66 has a bottom wall 66b that extends substantially forwardly of the aforementioned nip to be in underlying relationship to the rearward part of the transfer roll 65 of the machine with which the apparatus of this machine is used, the trough wall 66b from its front terminal edge being curved downwardly and thence upwardly to the location where its integrally joined with portion 66a. The lowermost part of portion 66b is at about the same elevation as wall portion 17a. The front terminal edge of portion 66b is at a substantially higher elevation than the lowermost part thereof, at a substantially lower elevation than the top edge of the front wall and a substantial distance forwardly of the front wall. The rear portion of trough 66 is located between the side wall portions of the pan side walls that extend forwardly of the lower portion of the front wall. Through the provision of the trough 66, drops of glue falling from the location of transfer of glue from roll 20 to roll 65 fall by gravity onto wall 66b to be collected by trough 66. The trough

66 is of the same width as the front wall of the glue pan and is removably mounted on transverse frame member 70 by suitable latches or clips (not shown). Frame member 70 is mounted by the side frame member.

5 The apparatus of this invention is mounted on a machine wherein the work conveyed by the conveyor 85 passes beneath the glue pan, the roll 65 being of a substantially larger diameter than roll 20 and extending to a substantially lower elevation than the bottom of the glue pan.

With the apparatus of this invention mounted on the machine with which it is to be used, and the sprocket 21 being driven in the direction of arrow 71 and roll 65 being driven in the direction of arrow 72, the pick up roll elevates glue thereon up to adjacent the premeter bar 40 where excess glue carried by the roll that is of a thickness greater than the spacing of roll 20 and bar 40 is stripped off the roll 20 and falls back into the glue pan. The glue remaining on the roll 20 is next carried to adjacent the metering roll where the excessive thickness of glue is stripped off, the metering roll drive and the location of the metering roll being such that the metering roll revolves slowly enough that the major portion of the glue which the meter roll strips off from the pick up roll will run off from the lower portion of the metering roll and return to the glue pan by gravity. In this connection the surface of the metering roll is of a material that the glue has a minimum tendency to adhere to the metering roll and will run freely back down into the glue pan. The glue carried by the pick up roll past the metering roll is carried to the transfer roll and transferred thereonto. Substantially all the glue that falls free of the pick up roll and the transfer roll at the nip thereof falls into either the glue pan or trough 66.

20 30 35 40 45 Due to transfer roll extending to a substantially lower elevation than both pick up roll and the pan 14 to transfer glue onto an article on conveyor 85 that pass beneath the pan, the pan cannot extend far enough forwardly of the pick up roll to catch much of the glue that falls onto trough 66.

To be noted is that the front wall 18 is inclined at an angle and extends sufficiently forward of the lower portion of the pick up roll and wall portion 17b is curved such that the interior walls of the pan are accessible for cleaning with scrapers, brushes, water and steam jets without the necessity for disassembling the glue pan or pick up roll from the side frame members.

What is claimed is:

1. For use with a machine having a rotary transfer roll for applying glue to an article on a conveyor, glue pot apparatus comprising a frame having side frame members, a glue pan mounted by said frame members, a pick up roll rotatably mounted by said frame members to pick up glue from said pan and transfer glue to said transfer roll, first means drivingly connected to the pick up roll for rotating said pick up roll in one direction, second means connected to the frame members for mountingly supporting the frame members on said machine in a position the transfer roll and pick up roll form nip portions adjacent a horizontal plane passed through the axis rotation of the pick up roll, said pan having a front wall extending to a maximum elevation that is at a lower elevation than said nip portions and horizontally adjacent a vertical plane passed through at least one of said nip portions and a string trough removably mounted on said frame adjacent said front wall, said trough extending forwardly of the front wall in un-

derlying relationship to the part of the transfer roll adjacent the pick up roll for catching glue falling from the nip portions.

2. The apparatus of claim 1 further characterized in that the front wall is inclined at a substantial angle to extend forwardly in an upward direction toward the pick up roll nip portion, that said trough has a first wall portion at least partially underlying the front wall and a second wall portion integrally joined to the first wall portion that extends substantially forwardly of the first wall portion, said second wall portion having an intermediate portion and a terminal edge remote from the first wall portion that is at a substantially lower elevation than the top edge of the first wall portion, substantially forwardly of the first wall portion and at a substantially higher elevation than the intermediate portion.

3. The apparatus of claim 1 further characterized in that a bar is stationarily mounted by the frame members in spaced relationship to the pick up roll for stripping off excess glue from the pick up roll and permitting the stripped off glue falling by gravity back to the glue pan, said bar being located relative the pick up roll angularly in the direction of rotation of the pick up roll to strip off the excess glue prior to glue being transferred to the transfer roll.

4. The apparatus of claim 3 further characterized in that a metering roll is resiliently mounted by the frame members adjacent the pick up roll angularly relative the pick up roll between said bar and the transfer roll.

5. The apparatus of claim 1 further characterized in that there is provided a glue container having a cover and an elongated spout mounted by the cover, bracket means mounted by the frame for mounting the container, said bracket means having a horizontal leg to supportingly engage the cover, said leg having a spout receiving slot opening horizontally outwardly and said spout being of a length to extend from the leg to within the confines of said pan.

6. The apparatus of claim 5 further characterized in that said leg has a vertical dowel receiving aperture horizontally spaced from said slot and that a dowel member is mounted by said cover for extending vertically into said aperture when the cover is seatingly supported on said leg.

7. The apparatus of claim 6 further characterized in that said pan extends a substantial distance rearwardly of the pick up roll, that said leg overhangs the pan rearwardly of the pick up roll, that said trough has a first wall portion extending forwardly of said front wall and curved upwardly in a forward direction, said first wall portion having a terminal front edge at a substantially lower elevation than the maximum elevation of the front wall, and that said pick up roll is of a substantially smaller diameter than said transfer roll.

8. For use with a machine having a rotary transfer roll for applying glue to an article on a conveyor, glue pot apparatus comprising a frame having side frame members, a glue pan mounted by said frame members, a pick up roll rotatably mounted by said frame members to pick up glue from said pan and transfer picked up glue to said transfer roll, first means drivingly connected to the pick up roll for rotating said pick up roll in one direction, a metering roll, second means for mounting the metering roll on the frame members in overhanging relationship to the glue pan and resiliently

retaining the meter roll adjacent the pick up roll for stripping off excessive thickness of glue from the pick up roll, and a glue strip off bar stationarily mounted on the side frame members in spaced relationship to the pick up roll for stripping excess glue off the pick up roll prior to the picked up glue being moved adjacent the metering roll by the pick up roll, said bar being mounted in overlying relationship to the glue pan and said second means mounting the metering roll above said bar and angularly spaced relative said bar in the direction opposite the direction of rotation of the pick up roll.

9. The apparatus of claim 8 further characterized in that the glue pan has a front wall in underlying relationship to the pick up roll, a bottom wall and a rear wall substantially rearwardly of the pick up roll, said bottom wall having an arcuately curved wall portion underlying the pick up roll that extends to a substantially lower elevation than the remainder of the bottom wall, said bar being intermediate the pick up roll and the rear wall.

10. The apparatus of claim 9 further characterized in that said front wall has a lower edge integrally joined to said arcuate wall portion and being inclined upwardly and forwardly to terminate at an elevation substantially below the axis of rotation of the pick up roll.

11. For use with a machine having a rotary transfer roll for applying glue to an article on a conveyor, glue pot apparatus comprising a frame having side frame members, a glue pan mounted by said frame members, a pick up roll rotatably mounted by said frame members to pick up glue from said pan and transfer picked up glue to said transfer roll, said pickup roll being of a substantially smaller diameter than the transfer roll, first means drivingly connected to the pick up roll for rotating said pick up roll in one direction, a metering roll, second means for mounting the metering roll on the frame members in overhanging relationship to the glue pan and resiliently retaining the meter roll adjacent the pick up roll, a glue strip off bar stationarily mounted on the side frame members in spaced relationship to the pick up roll for stripping excess glue off the pick up roll prior to the picked up glue being moved adjacent the metering roll by the pick up roll, said bar being mounted at a lower elevation than the metering roll and in overlying relationship to the glue pan, the glue pan having a front wall in underlying relationship to the pick up roll, a bottom wall and a rear wall substantially rearwardly of the pick up roll, said bottom wall having an arcuately curved wall portion underlying the pick up roll that extends to a substantially lower elevation than the remainder of the bottom wall, said bar being intermediate the pick up roll and the rear wall, and a string trough removably mounted on the frame adjacent the front wall for catching glue falling from the pick up and transfer rolls adjacent the area of transfer of glue, said trough having a wall portion extending substantially forwardly of the front wall that has a front terminal top edge at a substantially lower elevation than the maximum elevation of the front wall.

12. For use with a machine having a rotary transfer roll for applying glue to an article on a conveyor, glue pot apparatus comprising a frame having side frame members, a glue pan mounted by said frame members, a pick up roll rotatably mounted by said frame members to pick up glue from said pan and transfer picked

up glue to said transfer roll, first means drivingly connected to the pick up roll for rotating said pick up roll in one direction, a metering roll, second means for mounting the metering roll on the frame members in overhanging relationship to the glue pan and resiliently retaining the meter roll adjacent the pick up roll, and a glue strip off bar stationarily mounted on the side frame members in spaced relationship to the pick up roll for stripping excess glue off the pick up roll prior to the picked up glue being moved adjacent the metering roll by the pick up roll, said bar being mounted at a lower elevation than the metering roll and in overlying relationship to the glue pan, the glue pan having a front wall in underlying relationship to the pick up roll, a bottom wall and a rear wall substantially rearwardly of the pick up roll, said bottom wall having an arcuately curved wall portion underlying the pick up roll that extends to a substantially lower elevation than the remainder of the bottom wall, said bar being intermediate the pick up roll and the rear wall, and a glue container having a cover and an elongated spout attached to said cover and bracket means mounted by said frame, said bracket means including a horizontal leg in overhanging relationship to said glue pan, said leg having a spout receiving slot opening horizontally outwardly for having the spout moved horizontally thereinto, said cover being seatable on said leg with the spout extending through the slot and into the glue pan, said cover and leg having cooperating means for releasably retaining the cover on the leg while freely permitting the cover being freely moved vertically upwardly from the leg.

13. Glue pot apparatus comprising a frame, a glue pan mounted on the frame, a pick up roll rotatably mounted on the frame for picking up glue from the pan, a bracket mounted on the frame and having a horizon-

tal leg in overhanging relationship to the glue pan in substantial vertical spaced relationship to the pan, said leg having a slot opening horizontally outwardly remote from the frame and horizontally offset from the pick up roll, and a glue container having a container member, a cover on said container member and seatable on the horizontal leg, an elongated spout attached to said cover to open into said container member and extendable through said slot and into said glue pan when the cover is seated on said leg, and cooperating means on said cover and the leg for releasably retaining the cover seated on the leg.

14. The apparatus of claim 13 further characterized in that said cooperating means includes a leg portion having a dowel receiving aperture and a dowel member extending outwardly of the cover for extension into said aperture.

15. The apparatus of claim 14 further characterized in that said spout has an annular flange within the cover, and that said dowel member comprises a bolt for securing the flange to the cover.

16. The apparatus of claim 14 further characterized in that the glue pan has a front wall that at least partially underlies the pick up roll, that a string trough is mounted on the trough adjacent the front wall that extends forwardly of the front wall at a lower elevation than the maximum elevation of the front wall for catching picked up glue that falls forwardly of the front wall, and that a stationary premeter bar is mounted by the frame adjacent the pick up roll for stripping off excess glue from the pick up roll, said bar being mounted at an elevation below the horizontal plane of the axis of rotation of the pick up roll.
